SAFETY RAZOR BLADE

Louis Becker, Brooklyn, and Albert Storch,
New York, N. Y.

Application August 14, 1933, Serial No. 684,982

7 Claims. (Cl. 30—94)

This invention relates to new and useful improvements in a blade for safety razors.

This invention proposes the construction of a blade for a safety razor or other similar razor which is characterized by the fact that it has more cutting edges than the conventional safety razor blade without requiring more material.

Still further the invention particularly proposes increasing the cutting edges of a standard two edge blade so that it has four cutting edges, without an increase in the material from which the blade is constructed.

Still further the invention contemplates an arrangement whereby a plurality of flat narrow blades with cutting edges at the sides are positioned in the horizontal and associated with a means for holding the blades as a unit for engagement into a safety razor so that certain of the edges (the outer edges) of the blades are exposed for use, and whereby the blades may be adjusted so that the other cutting edges are repositioned to constitute the outer edges and then are exposed for use.

Still further the invention contemplates the arrangement of flat narrow blades with cutting edges at the sides and positioned parallel to each other, and end elements cooperatively associated with the blades for holding the blades as a unit for engagement into a safety razor so that the outer edges are exposed for use, and wherein the blades may be adjusted so that the other cutting edges constitute the outer edges exposed for use.

As another object of this invention it is proposed to associate end elements with the ends of a plurality of flat narrow blades having cutting edges at the sides in a manner so that the blades may be held with either of the cutting edges disposed outwards, and wherein the member itself is adapted to be associated with the standard parts of a safety razor, that is, the cap plate and the guard plate for the purpose of holding the blade as a unit within the safety razor ready for use.

Furthermore as another object of this invention an arrangement is proposed whereby a member is adapted for association in a safety razor, a plurality of flat narrow blades with cutting edges at the sides are arranged in the horizontal, and cooperative means arranged upon the member and blades for holding these parts as a unit simulating a conventional blade for a safety razor.

The invention also proposes a provision whereby the flat narrow blades previously mentioned are equipped with handles by which they may be

readily adjusted from one to the other of their positions of exposing either of their edges.

Still further the invention proposes the construction of articles as mentioned which are simple and durable and which may be manufactured and sold at a reasonable cost.

For further comprehension of the invention, and of the objects and advantages thereof, reference will be had to the following description and accompanying drawing and to the appended claims in which the various novel features of the invention are more particularly set forth.

In the accompanying drawing forming a material part of this disclosure:—

Fig. 1 is a plan view of a blade for a safety razor constructed according to this invention.

Fig. 2 is a sectional view taken on the line 2—2 of Fig. 1.

Fig. 3 is a view similar to Fig. 2 but illustrating the blade associated with the cap plate and guard plate of a safety razor.

Fig. 4 is a perspective view of the blade according to this invention, illustrated with the parts from which it is constructed slightly separated, only for the purpose of better disclosing the details.

Fig. 5 is a view similar to Fig. 1 but illustrating another embodiment of the invention.

Fig. 6 is another view of Fig. 1 illustrating another modified form of the invention.

Fig. 7 is a sectional view of the member of the blade construction, seen as though looking on the line 7—7 of Fig. 6, the narrow blades being removed.

Fig. 8 is a fragmentary enlarged sectional view taken on the line 8—8 of Fig. 7.

Fig. 9 is another view similar to Fig. 1 but illustrating another variation of the invention.

Fig. 10 is a sectional view as though taken on the line 10—10 of Fig. 9 but illustrated without the blades.

Fig. 11 is a fragmentary view similar to Fig. 1 but illustrating another embodiment of the invention.

Fig. 12 is an elevational view seen as though looking in the direction of the line 12—12 of Fig. 11, but illustrated with the blades removed.

Fig. 13 is a fragmentary elevational view of one of the blades seen as though looking in the direction of the line 13—13 of Fig. 11.

Fig. 14 is a front elevational view of the cap plate, the guard plate, and a blade according to this invention shown assembled.

The blade for safety razors according to this invention comprises a plurality of narrow flat

blades 10 with cutting edges 11 at the sides and positioned parallel to each other, in the horizontal and associated with a means for releasably holding said blades as a unit for engagement into a safety razor so that the outer edges are exposed for use. More particularly the means referred to according to the form of the invention illustrated in Figs. 1-4 comprises end elements 12 having dove-tailed projections 13 adapted to engage in similar cutouts 14 formed in the ends of the blades for holding the blades as a unit.

The cutouts 14 are extended through the thickness of the blades so that the end elements 12 may be assembled by just sliding the element into position so that the tongues 13 engage the openings 14. When the blade is engaged in the safety razor the cap plate and guard plate of the safety razor will prevent the blades 10 from becoming disconnected from the end elements 12 in that these parts will be held against relative up and down motion.

The elements 12 are so constructed to facilitate the engagement of the blade within a conventional safety razor. For this reason, a fork shaped projection 15 is arranged upon the inner sides of each of the elements 12. These fork shaped projections 15 are adapted to engage the conventional central rib formed upon the cap plate of the safety razor. This rib is schematically illustrated by the dot and dash lines 16. The dot and dash lines 17 illustrate the cap plate of a razor. This cap plate is shown formed at the corners with projections 18, as is a construction of a popular brand of razor blades sold on the market at the present time.

The end elements 12 are so arranged that the projections 18 engage against the ends thereof and in this manner the blade is safely and securely held within the razor. In Fig. 1 the blades 10 are shown having their edges numbered 1, 2, 3 and 4. With this arrangement records may be kept as to the number of times each of the edges are used so that the most satisfactory services can be obtained from the blades. As illustrated the blades 10 are shown with one of their edges disposed upon the outside. These blades may be disengaged from the end elements and turned around through 180° and then reengaged in place so that the edges which were previously towards the inside are now disposed towards the outside and ready for use when the blade is engaged into a safety razor.

In Fig. 3 a sectional view has been illustrated in which the cap plate 17 is shown coacting with the guard plate 19 holding the blade according to this invention in place. From this illustration it will be readily understood that only the outer edges of the blades 10 are in position for use. A feature of this invention resides in the fact that without adding any additional material to that now generally used for the blades of a safety razor, two additional edges are obtained and thus the operative life of the razor doubled.

In Fig. 5 a slight variation of the invention has been disclosed in which the blade is substantially identical to the form previously described except for the fact that end elements are used which distinguish from the previous end elements in having large projections 15' upon the inner sides arranged so as to engage in a different type of safety razor. The large projections 15' are formed with several curved portions 20 and 21 arranged to produce openings for the passage of studs. This razor blade is adapted for use in safety razors equipped with studs projecting from.

the cap plate through the guard plate as has been a very popular design in the past. There are large numbers of these razors still held by the public and with the arrangement disclosed in Fig. 5 the blade according to this invention 5 may be used in that particular type of safety razor.

In Figs. 6 and 7 another variation of the invention has been disclosed in which the blade is equipped with a member 22 having several 10 openings 23 for receiving the various studs which are projected from the cap plate through the guard plate of razors now on the market. This form of the invention distinguishes from the previous form in the arrangement of transverse end 15 portions 24 on the member 22 and of a greater thickness than the member 22, and arranged to adjustably hold the blades 10. More particularly the ends of each of the portions 24 are formed with projections 25, constituting fork constructions for engagement upon both sides of the blade 10 simultaneously. Located between the fork projections 25 and upon the end portions 24 there are projections 26 adapted to engage into niches 27 upon the blades 10 for the 25 purpose of holding the blades against displacement. With this arrangement the blades 10 must be snapped into and out of position. With this arrangement it is possible to reverse the blades whenever desired by merely flexing the 30 blades to cause them to bend and allow the disengagement.

In Figs. 9 and 10 another variation of the invention has been disclosed which is very similar to the previous form except for the fact that this blade is formed with a holder 22' having a longitudinal slot 28 in addition to the openings 23 to adapt it to more than one type of safety razor now on the market. The member 22' is provided with end portions 24' formed with openings 29 adapted to receive small tongues 30 projecting from the ends of the blades 10. With this arrangement it is necessary that the blades 10 be slightly flexed at the centers to disengage the tongues 30 from the openings 29 for the removal of the blades. With this arrangement it is possible to reverse the blades as previously described. The tongues 30 are of flat construction engaging in the round openings 29, so that the blades are firmly held from falling out but may 50 be rotated without removing the blades from the end portions 24'.

In Figs. 11-13 inclusive, another modified arrangement of the blade according to this invention has been disclosed which distinguishes 55 from the previous type in the provision of a member 22^a having cutouts at the ends producing a fork construction 32. The inner faces of this fork construction are formed with small longitudinal recesses 33 for receiving a shank in a 60 manner so that the shank may snap into place. With this arrangement the blade 10 is provided, which has tongues 34 projecting from the ends. These tongues are permanently engaged with studs or socket elements or shanks 35 adapted 65 to engage the fork 32 and snap into the recesses 33. The studs 35 are formed with heads 36 adapted to normally be disposed outside of the portions 24^a in a manner so that the blades 10 may be reversed without their removal from the holding member, by merely gripping the heads 36 and turning the heads to cause turning of the blades.

In Fig. 14 an assembly of the cap plate 17 and the guard plate 19 has been disclosed in conjunction with a blade according to this invention. 75

The blade is shown to comprise the blade portions 10 which are disposed in between the cap plate 17 and 19 and which have their ends slightly projecting and the enlarged end portions 24 previously described. The purpose of this view is to illustrate the manner in which the end portions 24 are located outside of the area of cap plate and guard plate so that the construction and assembly of the device may be readily understood.

10 It is to be understood that the blade holders may be made of any suitable material, such as metal, composition, etc. and that the blades may be either sold with the said blade holders or separately for filling the blade holders.

15 While we have shown and described the preferred embodiment of our invention, it is to be understood that we do not limit ourselves to the precise construction herein disclosed and the right is reserved to all changes and modifications coming within the scope of the invention 20 as defined in the appended claims.

Having thus described our invention, what we claim as new, and desire to secure by United States Letters Patent is:—

25 1. A blade for safety razors, comprising a plurality of flat narrow blades with cutting edges at the sides and positioned parallel to each other in the horizontal, and means for holding said blades in a unit for engagement into the safety 30 razor so that the outer edges are exposed for use and including trunnions on the longitudinal axes supporting the blades so that the blades themselves may be adjusted by turning on their longitudinal axes so that the other cutting edges constitute the outer edges.

2. A blade for safety razors, comprising a plurality of flat narrow blades with cutting edges at the sides and positioned parallel to each other in the horizontal, and means for holding said blades in a unit for engagement into the safety 40 razor so that the outer edges are exposed for use and including trunnions on the longitudinal axes supporting the blades so that the blades themselves may be adjusted by turning on their longitudinal axes so that the other cutting edges constitute the outer edges, said means for holding the blades being arranged for releasably holding the blades.

3. A blade for safety razors, comprising a plurality of flat narrow blades with cutting edges at the sides and positioned parallel to each other in the horizontal, and means for holding said blades in a unit for engagement into the safety 50 razor so that the outer edges are exposed for use and including trunnions on the longitudinal axes supporting the blades so that the blades themselves may be adjusted by turning on their longitudinal axes so that the other cutting edges constitute the outer edges, said trunnions being upon 55 the ends of the blades.

4. A blade for safety razors, comprising a plurality of flat narrow blades with cutting edges at the sides and positioned parallel to each other in the horizontal, means for holding said blades 60 in a unit for engagement into the safety razor

so that the outer edges are exposed for use and including trunnions on the longitudinal axes supporting the blades so that the blades themselves may be adjusted by turning on their longitudinal axes so that the other cutting edges constitute 5 the outer edges, and handles connected with said trunnions for turning the blades.

5. A blade for safety razors, comprising a plurality of flat narrow blades with cutting edges at the sides and positioned parallel to each other 10 in the horizontal, and means for holding said blades in a unit for engagement into the safety razor so that the outer edges are exposed for use and including trunnions on the longitudinal axes supporting the blades so that the blades themselves may be adjusted by turning on their longitudinal axes 15 so that the other cutting edges constitute the outer edges, said means comprising a member for association in cooperation with the cap plate and guard plate of a safety razor and 20 having enlarged end portions formed with fork constructions at the ends, and said trunnions being upon the ends of said blades and engaging within said forks.

6. A blade for safety razors, comprising a plurality of flat narrow blades with cutting edges at the sides and positioned parallel to each other in the horizontal, and means for holding said blades in a unit for engagement into the safety 30 razor so that the outer edges are exposed for use and including trunnions on the longitudinal axes supporting the blades so that the blades themselves may be adjusted by turning on their longitudinal axes so that the other cutting edges 35 constitute the outer edges, said means comprising a member for association in cooperation with the cap plate and guard plate of a safety razor and having enlarged end portions formed with fork constructions at the ends, and said trunnions being upon the ends of said blades and engaging within said forks, the sides of said forks being formed with recesses engageable by said trunnions so that the trunnions may snap into 40 and from positions.

7. A blade for safety razors, comprising a plurality of flat narrow blades with cutting edges at the sides and positioned parallel to each other in the horizontal, and means for holding said blades in a unit for engagement into the safety 45 razor so that the outer edges are exposed for use and including trunnions on the longitudinal axes supporting the blades so that the blades themselves may be adjusted by turning on their longitudinal axes so that the other cutting edges constitute 50 the outer edges, said means comprising a member for association in cooperation with the cap plate and guard plate of a safety razor and having enlarged end portions formed with fork constructions at the ends, and trunnions being upon 55 the ends of said blades and engaging within said forks, said trunnions being provided with heads 60 extended outside of said fork members.
